OPERATION OF CENTRIFUGAL-COMPRESSOR PLANTS.

1,263,056.

Specification of Letters Patent. Patented Apr. 16, 1918.

Application filed February 7, 1916. Serial No. 76,714.

To all whom it may concern:

Be it known that I, BENJAMIN GRAEMIGER, a citizen of the Republic of Switzerland, residing at 19 Hardturmstrasse, Zurich, Switzerland, have invented new and useful Improvements in the Operation of Centrifugal-Compressor Plants; and I do hereby declare the following to be a full, clear, and exact description of the invention, 10 such as will enable others skilled in the art to which it appertains to make and use the same, reference being had to the accompanying drawings, and to letters or figures of reference marked thereon, which form a 15 part of this specification.

The present invention has reference to an improved method for operating an auxiliary engine in centrifugal compressor plants for moving gaseous media.

20 The invention essentially resides in the novelty that the auxiliary engine required for operating a centrifugal compressor plant is in turn driven by the medium (air or gas) compressed in the compressor, and that 25 this medium is withdrawn from the compressor at a point in the rear of the second rotor wheel or impeller and is conducted back into the compressor at a point back of the first rotor wheel. Thus, for driving 30 the auxiliary engine a part of the moved medium is used which has already been compressed to a higher extent than could be obtained by the first rotor wheel, and its tension is reduced in the auxiliary engine 35 only to the pressure obtaining back of the first impeller. The auxiliary engine, thus, uses a part of the moved medium of considerably lower specific volume than the specific suction volume amounts to, so that the 40 effective cross-sections of the auxiliary engine, necessary for handling this volume, need not show unduly large values.

This method is especially advantageous if the medium for driving the auxiliary 45 engine is withdrawn from behind the last rotor wheel of the compressor and is then reintroduced into the intake space of this last rotor wheel, so that this portion of the medium describes a cycle which comprises 50 the last compression stage and the auxiliary engine.

The advantages of the described steps may be summed up as follows:—For the purpose of obtaining in the auxiliary tur-

bine low velocity of the motive fluid, conducive to low peripheral speed of the rotor and thereby simple construction of this turbine, the drop of pressure of only one stage of the compressor is made use of. This in itself requires a relatively large volume of 55 motive fluid, and for the purpose of reducing this volume and holding down the operative dimensions of the turbine, it is of advantage to use only the last pressure stage 60 of the compressor. To this is added one 65 more advantage as relates to the construction and operation of the compressor on decreasing the volume of moved medium. Because in the auxiliary turbine the pressure of only a few stages, even if only one 70 such, is used, a relatively high percentage of the total amount of moved medium handled is required for the auxiliary turbine operation. This amount normally remains stationary, no matter whether the compressor 75 is required to supply much or little compressed medium.

According to the present invention, only the pressure of the higher stages, or even only that of the very last impeller of the 80 last stage, is to be used, with the result that the volume of gas handled by the impellers of these last stages, or of the very last impeller thereof, is subjected to very little fluctuation.

85 Experience has shown that the "pumping" in air or gas compressors on decrease of moved medium does not set in nearly so early, if in some manner care is taken to prevent the last stages from reaching the 90 critical supply minimum. The last stages, then, exert a favorable influence on the preceding stages, as regard the pumping. Inasmuch as the last impellers, in the present instance, have to deal with a considerably 95 higher amount of medium than in prior methods, their effective cross-sections need not be cut down to those required by the decrease of the specific volume, which in the old style compressor was always regarded 100 with much disfavor in shop practice.

The portion of the motive medium used by the auxiliary engine shows the highest temperatures obtaining in the compressor, and it can thus be considerably cooled-off, 105 after it has passed out of the auxiliary engine, so that it can then, on re-introduction into the compressor, act as cooling medium

on the air or gas therein, thereby enhancing the efficiency of the compressor.

The present invention obviates the use of a special source of power for operating the auxiliary engine. In cases where formerly the compressor was driven by a steam turbine, generally also a small steam turbine was employed for actuating the auxiliary engine for condensing purposes. Figures 10 will show that the total steam consumption in the present instance is at least just as favorable as when using an auxiliary steam turbine, which turns its exhaust into the main turbine. Moreover, the air turbine, 15 according to the present proposed method, will be of considerably lighter, simpler and cheaper construction, and can be constructed also for such low output where an auxiliary steam turbine could not be considered. To 20 use an electric-motor in place of a steam turbine is not feasible in many instances for various obvious reasons.

I am aware that pumping plants are already in operation where part of the moved 25 water is used for operating an auxiliary engine, but such plants, obviously, cannot anticipate my invention for the reason that there the waste water is turned back into the intake channel, that is to say its pressure is 30 reduced to that obtaining just ahead of the first impeller of the centrifugal pump, and for the further reason that there the auxiliary engine has to deal with a motive medium, the volume of which, no matter what 35 the pressure increase, will not substantially be affected, so that the water plant cannot to a full degree make use of the advantages, which are the result of my method, dealing with a gaseous, compressible medium.

40 In the accompanying drawing is shown a plan view, partly in section, of a four stage centrifugal compressor with auxiliary turbine.

The compressor sucks-in air through the 45 intake 1 and exhausts it through connecting branch 2, with which communicates the conduit 3 leading part of the air acted on by the impeller or rotor section 7 to the rotary auxiliary engine (air turbine) 8, used for 50 instance for driving a cooling water pump 9. The latter sucks the water through connecting branch 10 and discharges it at 11. From the air turbine 8 the spent air is conducted through the connecting branches 12, 55 12^a into the space between the impellers 6 and 7, where it mixes with the newly arriving air, compressed by the preceding impellers 4, 5 and 6, and finally enters again the last impeller. Since for actuating the 60 auxiliary turbine 8 only the pressure difference generated by the last impeller 7 is used, the air in passing through the passage 13, with due consideration to the loss of pressure, assumes such a velocity as will best 65 operate a single, relatively small rotor 14.

The auxiliary turbine, therefore, is of the utmost simplicity, takes up little space and is cheap to manufacture. For starting the turbine 8 either auxiliary pressure air, provided by a separate compressor or pressure 70 receptacle, or steam may be introduced through the pipe 15. The steam would be exhausted through 16. Between the turbine and the compressor a cooler 17 may be interposed, for cooling the spent air to such 75 a degree, that it could cool in turn the compressed and thereby highly heated air in the space between the impellers 6 and 7. The cooling water is introduced into this cooler 17 at 23, and is carried off at 24.

80 Calculations show that, for instance, with a compressor, which sucks in hourly 10,000 m³, i. e., almost 12,000 kilograms of air and compresses it to 8 atmospheres, at the conduit 3, back of the last impeller 7, 9600 kilograms of air per hour may be drawn off for 85 operating the air turbine 8, which latter drives the condensers necessary for the operation of the compressor turbine.

80 The weight ratio of the auxiliary air, which is used in a cycle, to the total amount of air moved is = 100:80, that is to say, if the impellers in advance of the last one impel 100 weight-parts of air, the last impeller will have to impel 180 parts. If, then, the 95 amount of useful air is reduced to one-fourth of its normal value, the last impeller will still have to handle 105 weight-parts and is thus safeguarded against pumping. Relative to the normal rate these 105 parts 100 would be equal to 58% (105:180). As above stated, also the preceding stages would be safeguarded against pumping, notwithstanding that their rate, in the example chosen, would be only 25% of the normal. 105 The internal diameters (effective cross-sections) of the last impeller will have to be enlarged by 80% over plants where my improvements are not employed. For this reason the last impeller is of such dimensions 110 that the operative passages can readily be work.

Owing to the cycle described by the supply medium between the impeller 7 and the turbine 8, this last impeller 7 has, even on a 115 light load, still to deal with such a large air volume that it is prevented from pumping or surging and can thus lower the critical limit at which pumping in the preceding stages will begin.

120 The indispensable blowing-off cock 18 communicates by the conduit 19 with the compressor space back of the impeller 6, with the advantage that by this arrangement the blowing-off operation does not interfere with the compression in the last impeller. It may be found necessary to install a second blowing-off cock 20 back of the last impeller 7, which would operate only later 125 and which could conveniently be built into 130

the overflow or by pass conduit 21. The blowing-off air is carried to the rotor 14 of turbine 8 by special guide passages 22. This air then passes through the conduits 12, 12^a, 5 19 and the cock 18 into the atmosphere or into the suction conduit of the compressor.

I claim.

1. In the operation of compressors having a plurality of stages, the method which comprises maintaining a flow of compressed medium from one of the higher compression stages, translating the energy of the medium so removed, separately applying the translated energy and returning the medium to 10 a lower pressure stage beyond the initial stage.

2. In the operation of compressors having a plurality of stages, the method which comprises by-passing compressed medium 20 from a higher to a lower stage beyond the first stage, and translating and separately applying energy of the medium during the passage from said higher to said lower stage.

25 3. In the operation of compressors having a plurality of stages, the method which comprises discharging compressed medium from a high compression stage into a lower compression stage beyond the first stage, translating energy of the medium thus transferred and increasing the density of 30 said medium after translation but before entry into said lower stage.

4. In the operation of compressors having 35 a plurality of stages, the method which comprises discharging compressed medium from a high compression stage into a lower compression stage beyond the first stage, translating energy of the medium while expanding it and then cooling the expanded 40 medium before returning it to said lower stage.

5. In the operation of compressors having a plurality of stages, the method which comprises discharging compressed medium from 45 the highest compression stage into another compression stage beyond the first stage and translating the energy of the medium during its transfer between the two stages.

50 6. In the operation of compressors having a plurality of stages, the method which comprises discharging compressed medium from a high stage to a lower stage and translating energy of the medium thus transferred to an extent substantially equivalent 55 to the energy difference of the medium between the two stages.

7. In the operation of compressors having a plurality of stages, the method which comprises maintaining a continuous discharge 60 of compressed medium from a higher stage to a lower stage of compression beyond the first stage, translating energy of said medium during such discharge, and at times venting compressed medium for gov-

erning purposes from the delivery conduit of the highest stage and separately translating energy of the vented medium.

8. In the operation of compressors having a plurality of stages, the method which comprises discharging compressed medium from a high stage of compression into a lower compression stage, translating energy of the medium during its passage from the high to the lower stage and blowing off medium 70 at a stage of compression lower than that from which the translated medium is taken, thereby maintaining the energy in the medium to be translated during blowing-off periods.

9. In the operation of compressors having a plurality of stages, the method which comprises discharging compressed medium from a high stage of compression into a lower compression stage, translating energy of 75 the medium during its passage from the high to the lower stage and blowing off medium at a stage of compression lower than that from which the translated medium is taken, thereby maintaining the energy in the medium to be translated during blowing-off periods, and separately diverting medium from the delivery stream of the compressor and translating energy 80 thereof for governing purposes.

10. In combination in a centrifugal compressor plant, a multi-stage compressor, an auxiliary machine driven by compressed medium from a high stage of said compressor, and means to discharge the medium 100 from said machine into a lower stage of the compressor.

11. In combination in a centrifugal compressor plant, a multi-stage compressor, an auxiliary machine driven from the last 105 stage of the compressor, means to discharge the exhaust medium from said machine into a lower stage of the compressor, and blow-off at that stage of the compressor into which said machine discharges. 110

12. A centrifugal compressor plant, comprising a multi-stage centrifugal compressor, an auxiliary machine having an inlet and an outlet and driven by the medium compressed by said compressor, a connection from between a point of said compressor beyond at least the second impeller of said compressor and the said inlet, and a connection between a point of said compressor beyond at least the first impeller of 115 said compressor and said outlet.

13. In combination in a centrifugal compressor plant, a multi-stage centrifugal compressor, an auxiliary machine driven by the medium compressed by the compressor, 125 an inlet and outlet for said machine, a connection between the inlet and a point situated beyond the last impeller of the compressor, and a connection between the outlet of the auxiliary machine and a point 130

situated beyond the first impeller of the compressor.

14. In combination in a centrifugal compressor plant, a multi-stage centrifugal compressor, an auxiliary machine, an inlet and outlet for said machine, a connection between said inlet and a point situated beyond the last impeller of the compressor, and a connection between the outlet and a point situated beyond the last but one impeller of the compressor.

15. A centrifugal compressor plant, comprising a multi-stage compressor, and auxiliary machine having an inlet and an outlet and driven by the medium compressed

by said compressor, a connection from between a point of said compressor beyond at least the second impeller of said compressor and said inlet, a connection between a point of said compressor beyond at least the first impeller of said compressor and said outlet, and a cooler intercalated in said latter connection.

In testimony that I claim the foregoing as my invention, I have signed my name in presence of two subscribing witnesses.

BENJAMIN GRAEMIGER.
